US00D947565S

(12) **United States Design Patent** (10) **Patent No.:** **US D947,565 S**
(45) **Date of Patent:** **** Apr. 5, 2022**

(54) **ROLL TOWEL DISPENSER ROLLER TAB**

(71) Applicant: **Bradley Fixtures Corporation**,
Menomonee Falls, WI (US)

(72) Inventor: **Michael M. Starkey**, Kent, OH (US)

(73) Assignee: **Bradley Fixtures Corporation**,
Menomonee Falls, WI (US)

(**) Term: **15 Years**

(21) Appl. No.: **29/695,329**

(22) Filed: **Jun. 18, 2019**

Related U.S. Application Data

(63) Continuation of application No. 29/647,878, filed on
May 16, 2018, now Pat. No. Des. 854,347.

(57) **CLAIM**

I claim the ornamental design for a roll towel dispenser roller tab, as shown and described.

DESCRIPTION

This application is related to U.S. Des. Pat. App. Ser. No. 29/647,869, filed on May 16, 2018, entitled “housing for a roll towel dispenser,” which is also incorporated herein by reference in its entirety.

FIG. 1 is a top perspective view of a roll towel dispenser roller tab showing my new design;

FIG. 2 is a front side view of the claimed design of FIG. 1;
FIG. 3 is a rear side view of the claimed design of FIG. 1;
FIG. 4 is a right side view of the claimed design of FIG. 1;
FIG. 5 is a left side view of the claimed design of FIG. 1;
FIG. 6 is a top view of the claimed design of FIG. 1; and,
FIG. 7 is a bottom view of the claimed design of FIG. 1.
The ornamental design which is claimed is shown in solid lines in the drawings.

1 Claim, 5 Drawing Sheets
